UNITED STATES PATENT OFFICE

2,190,157

CENTRIFUGAL OPERATING MEANS FOR
FUSESHelmut Junghans, Schramberg-Sulgen, Germany
Application July 23, 1937, Serial No. 155,333

In Germany July 23, 1936

3 Claims. (Cl. 102—36)

This invention relates to centrifugal drive devices for projectile fuses and to a device of this kind having means for keeping the driving force constant during the whole period of flight, it being known that this force increases with increasing distance of a centrifugal weight from the axis of the projectile.

It has been proposed to provide an auxiliary centrifugal weight to compensate the varying driving force of a driving centrifugal weight, which auxiliary weight, particularly at the beginning of projectile flight when the force exerted by the main weight is still small, assists the latter but later when said force has increased, diminishes this assistance in a manner to maintain the driving force constant.

The object of the invention is to provide a mutual arrangement of main and auxiliary weights such that when the main weight has traversed a certain distance the auxiliary weight is automatically rendered inoperative thereby.

A further object of the invention is to provide an extremely simple arrangement of main and auxiliary weights occupying minimum space. The smaller the space occupied by a main weight and its auxiliary weight, the more sets of weights can be used, the caliber of the projectile being the same.

An embodiment of the invention is illustrated by way of example in the accompanying drawing.

Fig. 1 is a plan view of the fuse operating mechanism in the position of rest when the projectile is fired.

Fig. 2 is a similar view in the operative position shortly before the secondary weight is released from the primary weight.

Fig. 3 is a similar view of the operating mechanism with the secondary weight disconnected from the primary weight and located in the extreme position.

The toothed segment a^1 , which is pivoted at a and drives the mechanism by way of the toothed shaft f , carries the primary centrifugal weight b . About the same pivot a there is mounted a lever c , which carries the secondary weight d and possesses at the opposite end a projection e , by means of which the lever c bears against the primary centrifugal weight b when the operating mechanism is in the condition of rest.

The operation of the embodiment shown in the drawing is as follows:

When the projectile is fired the lever c , owing to the secondary weight d located well away from the centre of the fuse, presses forcibly with

its projection e against the weight b and assists the outward movement of the latter for such time as the secondary weight d has not reached the extreme position shown in Fig. 3. When, however, this movement has been completed 5 the weight d remains stationary and the primary weight b continues to move outwards, the projection c passing out of engagement and the effect of the auxiliary force of the secondary weight d on the primary weight b then ceasing. 10

What I claim as new and desire to secure by Letters Patent is:

1. In a time fuse for a projectile, a drive shaft for the timing mechanism of said fuse, a pivot member stationary with respect to the fuse, a 15 driving segment including a primary centrifugal weight mounted on said pivot, a lever member including a secondary weight on one end thereof freely mounted on said pivot, and means connecting said driving segment to said drive shaft 20 for actuating the same, the other end of said lever having means thereon constructed and arranged to bear on said primary weight under centrifugal forces caused by rotation of said projectile upon firing whereby both weights 25 actuate the drive shaft, until said secondary weight swings said lever to a maximum throw position, said segment and primary weight moving thereafter on said pivot alone to actuate the drive shaft whereby a substantially uniform drive is 30 effected.

2. In a time fuse for a projectile, a drive shaft for the timing mechanism of said fuse, a pivot member stationary with respect to the fuse, a 35 driving segment including a primary centrifugal weight mounted on said pivot, a lever member including a secondary weight on one end thereof freely pivoted on said segment, and means connecting said driving segment to said drive shaft for actuating the same, the other end of said 40 lever having means thereon constructed and arranged to bear on said primary weight under centrifugal forces caused by rotation of said projectile upon firing whereby both weights actuate the drive shaft, until said secondary weight 45 swings said lever to a maximum throw position, said segment and primary weight moving thereafter on said pivot alone to actuate the drive shaft whereby a substantially uniform drive is 50 effected.

3. In a time fuse for a projectile, a drive shaft for the timing mechanism of said fuse, a pivot member stationary with respect to the fuse, a driving segment including a primary centrifugal weight mounted on said pivot, a lever member 55

- including a secondary weight on one end thereof freely pivoted on said segment, and means connecting said driving segment to said drive shaft for actuating the same, the other end of said lever having means thereon constructed and arranged to bear on said driving segment under centrifugal forces caused by rotation of said projectile upon firing whereby both weights actuate

the drive shaft, until said secondary weight swings said lever to a maximum throw position said segment and primary weight moving thereafter on said pivot alone to actuate the drive shaft whereby a substantially uniform drive is effected.

HELMUT JUNGHANS.
